METALLIC DOOR

Filed Jan. 28, 1929

UNITED STATES PATENT OFFICE

JOHN C. WHITRIDGE, OF COLUMBUS, OHIO, ASSIGNOR TO THE BUCKEYE STEEL CASTINGS COMPANY, OF COLUMBUS, OHIO

METALLIC DOOR

Application filed January 28, 1930. Serial No. 335,571.

This invention relates to improvements in metallic doors, and especially to a novel drop door for gondola freight car purposes, but the invention is not limited to such application, but may be used in any environment where it is found particularly suitable.

Bottom drop doors for freight cars were first made of wood planks bound with structural metal shapes. Then came the door with rolled steel sheet in combination with rolled metal shapes. Afterwards, pressed steel doors, formed mainly by turning the edges and corrugating a piece of rolled steel sheet, came into use, and in a more recent design, such doors have been made wholly of cast steel.

The pressed steel doors, and also the doors built up of steel sheets and shapes, are open to the objection that they do not have the requisite stiffness; it being impossible to distribute the metal most advantageously at corners and other irregularities. Furthermore, a satisfactory fit between the door edges and car floor, is practically impossible to maintain because of the battering of the free edges, and the lightness of the material, and this results in heavy losses, by leakage of certain materials carried by the car.

The objection with a design wholly of cast steel resides in the fact that it is difficult to cast the sheet portion of the door thin enough so that the door as a whole, will be sufficiently light in weight to be practical. The present state of the steel foundry art would require casting the sheet too thick to be consistent with the required strength of the framework, and of the complete door. Attempts to cast thin sheets result in "misruns", and increasing their thickness makes the door unnecessarily heavy. These factors, through their bearing on the economies of production and manufacture, limit very materially, so far, the use of doors entirely of cast steel.

In order to eliminate these objections, I propose to make the door of a cast steel framework, combined with rolled steel sheet. By this combination, the sheet may be as thin as consistent with the strength required, and the framework upon which the sheet rests can be made as strong as desired. The frame-

work will include crossed ribs which not only support the sheet, but stiffen the framework. The portion of the framework which abuts the flooring, is of substantial section and is not easily bent or distorted.

From the foregoing it will be appreciated that the main object of my invention is to provide an improved door made up of a cast steel framework supporting a rolled steel sheet, with a view of eliminating the disadvantages of prior art structures.

With the foregoing object outlined and with other objects in view which will appear as the description proceeds, my invention consists in the novel features hereinafter described in detail, illustrated in the accompanying drawings, and more particularly pointed out in the appended claims.

Referring to the drawings,

Fig. 1 is a top plan view of the cast steel framework of my improved door.

Fig. 2 is a transverse vertical sectional view of the same, taken on line 2-2 of Fig. 1.

Fig. 3 is a longitudinal sectional view on the line 3-3 of Fig. 1, and showing a fragment of the car floor against which the edge of the door abuts.

Fig. 4 is an elevation of the outer or free end of the door framework.

Fig. 5 is a similar view of the inner or hinge end of the framework.

Fig. 6 is a side elevation of the framework, shown abutting at its hinged end against a portion of the floor of the car.

Fig. 7 is a sectional view of a detail, taken on line 7-7 of Fig. 1, and showing one means of connecting the rolled steel sheet to the framework.

Fig. 8 is a similar view of a modification, in which the rolled steel sheet is welded to the framework.

Before proceeding with a detail description of my invention, it may be well to call attention to the fact that when doors of the type which I have invented are employed as bottom drop doors for gondola freight cars, they may be opened and closed by the operating means commonly employed for this purpose. Such operating means usually consists of a rotatable shaft which cooperates with a

100

series of these doors, each of which has its inner end hinged to the longitudinal center sill of the car. The shaft rolls up and down in upwardly and outwardly inclined slots 5 provided in the body bolster and the intermediate supports, and each door has a pair of rails or "ways" on its under side, against which the supporting shaft bears and slides. These ways have an irregular but definite 10 contour which is most suitable for the operation of the door, and must be so formed, no matter of what material the door is made. Said supporting shaft is generally actuated by a lever and pawl mechanism, and when 15 the pawl is released, the shaft is permitted to roll down the slots and this allows all of the doors controlled by the shaft, to open and discharge the contents of the car beside the track. When the car has been emptied, the 20 entire series of doors may be closed by moving the operating lever back and forth for the purpose of actuating the pawl and ratchet, and rolling the shaft, guided by the usual chains, back up the slots to the closed 25 position.

Reverting now to the drawings, it will be noted that the framework A of the door is made of a single piece of cast steel which includes side bars B, end bars C, D, and a cruciform brace E, all integrally united. 30

Each side bar is provided at its longitudinal central portion with a depending rail or way F, and a depending marginal flange G, the latter being inclined as shown in Fig. 3, to cooperate with a similarly inclined surface H, of a doorway, that is located in the floor I. It will be seen that the portion which abuts the flooring, is of substantial thickness to prevent the same from being bent or distorted in use, and as the parts F and G are 40 integral with the side bar B, these parts mutually reinforce one another, thus making a stronger door with a saving in weight.

Each rail or "way" preferably extends the 45 full length of the side bar from which it depends, and is provided at its lower edge with oppositely extending reinforcing beads K, which provides a track of irregular lower surface, as best shown in Fig. 6.

The outer and inner end bars C and D are 50 also provided, each with a depending skirt or marginal flange L, joined at its ends to the flanges G of the side bars, and having its medial portion of greater depth than its end portions, to provide reinforcement for the outer edge portion of the door.

The cruciform reinforcement E is made up 55 of crossed bars M and N, and the ends of the bar M merge into the side bars of the framework, while the ends of the bar N merge into the end bars C and D. Said brace bars increase in depth from their end portions toward their medial portions or crossing point, and each brace bar has its 60 lower edge beaded, as shown at O, for rein-

forcing purposes, and the ends of each of these beads rises, as best shown in Fig. 3, and merges into the webs of the bars of the framework, (see P). This construction transfers strains from the beads to the webs of the bars 70 of the framework, thus making a basket or efficient beam construction for supporting the load carried.

The filleted construction about the corners of the framework, (see R), together with the above mentioned economies, that can be taken advantage of in cast steel, effect a substantial saving of the weight of the finished door, as compared with other types of equal strength. 75

The rolled steel sheet portion S of the door may be fastened to the framework, either by rivets, as shown at T in Fig. 7, or by welding, as shown at U, in Fig. 8. Such a sheet, if pierced accidentally or otherwise damaged, 80 may be readily renewed.

At this point, it may be noted that each of the side bars of the door is recessed at V, in order to permit the rolled steel sheet to be counter-sunk in the upper face of the framework, and the upper surface of the sheet to 90 lie in the same plane as the upper surface of the side bars of the framework.

By referring to Figs 1, 3 and 5, it may be seen that the inner ends of the rails converge as at W, and they terminate in hinge butts X 95 which are also integrally united with the depending flange of the end bar D.

Whenever it is feasible, openings Y are provided to reduce the weight of the framework. 100

While the drawings show a door useful particularly for a bottom opening in a gondola car, it is manifest that doors of the type which I have invented may be used on any other type of car to which it might be applicable. Of course, if the design were worked into a present day hopper car door structure, the contour of the rails F would become unimportant, and the rails themselves might be wholly or partially dispensed with, because 105 the operating mechanism of the type mentioned would not be used with doors of this type. 110

While I have disclosed what I now consider a preferred embodiment of the invention, it 115 will be apparent to those skilled in the art that various changes may be made in the details disclosed, without departing from the spirit of the invention, as expressed in the claims.

What I claim and desire to secure by Letters Patent is:

1. In a door, in combination, a cast steel framework including crossed brace bars, and a rolled steel sheet secured thereto. 125
2. In a door, in combination, a one-piece cast steel framework including crossed brace bars, and a rolled steel sheet secured thereto.
3. The combination in a door, of a one-piece steel framework having openings there- 130

- in and provided with a cruci-form brace, and a rolled steel sheet secured thereto and covering said openings.
4. The combination in a door, of a one-piece cast steel framework having openings therein and provided with a cruci-form brace, and a sheet metal covering for the openings rigidly secured to the framework.
5. In a metallic door, the combination of a cast steel frame and a rolled steel cover plate, said frame including an angular bar and a rail integrally connected with the bar and extending lengthwise of the latter.
- 10 6. In a metallic door, the combination of a cast steel frame and a rolled steel cover plate, said frame including a side bar of angular cross section, and a rail integral with the web of the bar, and extending lengthwise of the latter.
- 15 7. In a cast metallic door frame, brace bars provided at their outer edges with reinforcing beads.
8. A cast steel door framework, including crossed brace bars having their outer edges provided with integral reinforcing beads.
- 20 9. A cast steel door framework, including side bars, end bars and brace members connecting the same, certain of said bars having webs, and beads extending along the outer edges of the brace members, and merging into said webs.
- 25 10. In a cast steel door framework, an endless frame formed of side and end bars having webs, brace members connecting said bars, and integral beads on the outer edges of the brace members merging into said webs.
- 30 11. In a cast steel door framework, an endless frame having webs, a cruci-form reinforcement having its extremities united with the frame, and reinforcing beads extending along the cruci-form reinforcement, and merging into said webs.
- 35 12. A cast steel door framework, including a one-piece endless frame provided with webs, and a marginal flange, a cruci-form reinforcement integral with the frame, and reinforcing beads extending along the outer edges of the arms of the reinforcement, and merging into said webs.
- 40 50 13. A cast steel door framework, including a one-piece endless frame provided with webs, and a marginal flange, a cruci-form reinforcement integral with the frame, and reinforcing beads extending along the outer edges of the arms of the reinforcement, and merging into said webs, the arms of the cruci-form reinforcement gradually increasing in depth toward the crossing point of the arms.
- 45 60 14. A cast steel door framework, including a one-piece endless frame formed of an endless web and a continuous depending marginal flange, said flange at opposite ends of the frame, being gradually increased in depth toward the medial portions of the
- same, and brace members having their ends integrally united with said frame.
15. In a metallic door, the combination of a rolled steel cover plate and a cast steel framework, said framework comprising a bar provided with a flange, hinge butts integral with said flange, and reinforcing ribs integrally connecting the butts to other portions of the framework.
- 70 16. In a cast steel door framework, a one-piece endless frame having side and end bars, one of said end bars having a reinforcing flange, rails integral with the sides of the frame, hinge butts integral with said flange, and reinforcing ribs forming continuations of the rails and merging into the hinge butts.
- 75 80 17. In a cast steel door framework, a one-piece frame formed of an endless web having a continuous marginal flange, a cruci-form reinforcement having its ends integral with the frame, certain ends of the reinforcement merging into said flange, and reinforcing beads extending along the outer edges of the arms of the reinforcement and merging into said web.
- 85 90 18. In a cast steel door framework, a one-piece frame formed of an endless web having a continuous marginal flange, a cruci-form reinforcement having its ends integral with the frame, certain ends of the reinforcement merging into said flange, reinforcing beads extending along the outer edges of the arms of the reinforcement and merging into said web, a portion of the web being countersunk, and a metallic plate secured to the framework and arranged in the counter-sunk portion of the web.
- 95 100 19. In a cast steel door framework, a one-piece frame formed of an endless web having a continuous marginal flange, a cruci-form reinforcement having its ends integral with the frame, certain ends of the reinforcement merging into said flange, reinforcing beads extending along the outer edges of the arms of the reinforcement and merging into said web, and a pair of rails integral with opposite side bars of the frame, and merging at their ends into said flange.
- 105 110 115 In testimony whereof, I have signed this specification.
- JOHN C. WHITRIDGE.
